ROTATING REFLECTOR

Raymond C. Siebert, Avon, N. Y.

Application March 24, 1954, Serial No. 29,678

Term of patent 3½ years

(Cl. D72—1)

FIG. 1.

FIG. 2.

FIG. 3.

To all whom it may concern:

Be it known that I, Raymond C. Siebert, a citizen of the United States of America and resident of Avon, in the county of Livingston and State of New York, have invented a new, original, and ornamental Design for a Rotating Reflector, of which the following is a specification, reference being had to the accompanying drawing, forming part hereof.

Fig. 1 is an edge view or top plan view of a rotating reflector embodying the new design, with the rotor positioned approximately in the same plane with the mounting ring or frame;

Fig. 2 is a front elevational view of the same; and Fig. 3 is a perspective view of the same, with the rotor turned to a different position.

I claim:

The ornamental design for a rotating reflector, substantially as shown.
